Fig. 1 is a top plan view of a fishing lure showing my new design;

Fig. 2 is a side elevation of the same;

Fig. 3 is a front end elevational view looking from right to left in respect to Fig. 1;

Fig. 4 is a rear end elevational view;

Figs. 5, 6 and 7 are cross-sections on the lines 5—5; 6—6, and 7—7, respectively, of Fig. 2.

The dominant features of my new design reside in the full line portions of the drawings. The fishing hook and snap are omitted from Figs. 3 and 4 for convenience of illustration.

I claim:

The ornamental design for a fishing lure, as shown and described.
